CLOTHESLINE SHEATH

Ada P. Williams, Oakland, Calif.

Application December 7, 1935, Serial No. 53,328

6 Claims. (Cl. 211—119.18)

The invention relates to a means for temporarily covering a clothesline to prevent the direct contact of cloth articles mounted thereon with the line, whereby to protect the articles from rust and/or dust on the line.

A general object of the invention is to provide a sheath which forms a closed tube about the clothesline portion therein.

Another object is to provide a sheath of the class described which permits the application of usual clothes pins thereto for securing the articles in place on the clothesline.

A further object is to provide a sheath which utilizes a slide fastener device for effecting its closure and opening, whereby to provide for a particularly ready mounting and dismounting of the sheath.

An added object is to provide a means for automatically effecting the progressive mounting and dismounting of the sheath with respect to a pulley clothesline.

The invention possesses other objects and features of advantage, some of which, with the foregoing, will be set forth or be apparent in the following description of a typical embodiment thereof, and in the accompanying drawings in which,

Figure 1 is an elevation showing sheaths embodying my invention mounted on a continuous pulley line.

Figure 2 is a fragmentary exterior view of a sheath in open and flat condition.

Figure 3 is a fragmentary underneath view of a partly closed sheath on a clothesline.

Figure 4 is a side view of the partly mounted sheath, a runner for the slide fasteners thereof being shown as attached to a fixed element.

Figure 5 is an enlarged section at 5—5 in Figure 4.

Figure 6 is an enlarged sectional view at 6—6 in Figure 1.

Figure 7 is an enlarged elevation of a portion of the showing of Figure 1 at a sheath-mounting unit.

Figure 8 is a section at 8—8 in Figure 7.

Figure 9 is a plan view of the showing of Figure 7.

Essentially, the sheath of my invention comprises a length of tape 11 having complementary rows of like members 12 fixed directly to its opposite edges and arranged for interlocking to secure the tape edges together threat when the tape is formed into a tube and the members 12 of the two rows are engaged in mutually staggered and generally coplanar relation. The tape 11

may comprise a strip of any suitable wear-resisting and flexible material, and is preferably thickened at its opposite side edges to provide thickened rim portions to which the rows of members 12 may be directly and permanently secured. As 5 illustrated, the tape 11 comprises a strip of woven fabric.

The members 12 comprise generally U-shaped elements which span the tape edges and are clinched to said edges in evenly spaced relation. 10 At their cross portions, the members 12 are shaped to provide rearwardly projecting and tapered points and forwardly opening sockets which are complementary to the points. The members 12 of a row are so spaced that when 15 adjacent said members are mutually parallel; they may receive and retain the cross portion of a member of the other row between them, and, with the point of the latter member engaging in the socket of the front member of the pair while 20 its socket receives the point of the rear member of the pair for securing the engaged members against separation.

The engagement and disengagement of the members 12 of the two rows are arranged to be 25 effected by the use of a sliding runner or locking member 15 which is operative for simultaneously engaging the two rows of members to spread adjacent members of a row out of parallelism and so permit the engagement between them of a 30 member from the other row. The movement of the runner 15 along the rows from or to the forward tape end is arranged to progressively interlock or disengage the members of the two rows in accordance with the direction of motion of the 35 runner along the rows. It is noted that slide-controlled fasteners of the type now described are now in common use, and that the specific forms of the fastening members 12 and of the portions of the runners 15 which receive them 40 are generally immaterial to the present invention.

The locking runner 15 is of a usual one-piece structure wherein outer and inner plate portions 45 16 and 17 are mutually parallel and are mutually connected solely at one end by a narrowed plate portion 18 which is arranged to engage between the rows of members 12 to be connected while 50 said rows of members extend longitudinally therethrough in guideways at the opposite runner sides and in converging lines in such a manner that the two rows of members meet for their interlocking within the runner. A handle or pull tab 19 is provided in the runner portion 55 16 for use in effecting the sliding of the runner 55

along the rows of fasteners 12 to engage or disengage the latter. As shown, the pull tab 18 is hingedly secured to the plate 16 and is provided with an opening 20 adjacent its free end.

5 Since it will usually be desirable to completely remove a sheath from about a clothesline, particularly if the latter is out of doors, or to mount a sheath on a line without dismounting the same from its supports, means are preferably provided 10 for the detachable engagement of at least one row of fastening members with the runner 15, such a means being illustrated in Figures 2 and 3.

As shown, a special one-piece member 22 is fixed to an edge of the tape at its forward end portion, said member providing a terminal stop 23 and a U-shaped guide-way 24, both extending in the plane of the tape portion thereof. The opposite tape edge portion is provided with a bead member 25 for sliding engagement in the 20 guideway 24. When the runner 15 is mounted on the tape edge at the member 22 and is disposed against the member, the bead 25 may be inserted therethrough and in the guideway 24 to engage the stop 23, after which the runner 25 may be moved along the row of hooks 12 to engage them in the described manner to provide a tubular sheath. The member 22 and the bead member 25 may be formed of sheet metal and may be clinched or riveted to the tape in their respective positions, it being understood that said members cooperate to insure a proper starting for the closing of the tape to provide a sheath. Stops 26 may be provided at the rear tape end to prevent a detachment of the runner 15 thereat.

35 It will now be noted that a strip of the tape carrying the described fastening assembly may be mounted on a clothesline by laying the strip upon the line, engaging the bead 25 in the member 22 in the described manner and while the 40 runner is disposed immediately adjacent the member 22, and then effecting a relative movement of the runner and tape longitudinally of the tape. With the fasteners of the mounted sheath at its lower side, the clothing thereon does 45 not contact the fasteners and the placement of clothes pins over the cloth articles and sheath is facilitated. It will be understood that the tape may be held fixed and the runner 15 moved therealong, or the runner may be held fixed while the tape is moved longitudinally of itself. The 50 former method would be used in mounting the present sheath on a fixed line, while the latter method is particularly useful when the line 31 is continuous and extends between pulleys 32 in a usual manner, said pulleys extending from fixed 55 hooks 33.

In Figure 1, a sheath 27 embodying the present invention is shown as being fully mounted on the line 31, while a second and similar sheath 28 is 60 shown as only partly mounted on the line and as being engaged with a sheath-mounting unit 35 for facilitating the mounting of the sheath on the pulley line. The unit 35 essentially provides a means to dispose the sheath in overlying 65 relation to the line and clear of the line at its unmounted portion, and secures the runner 15 against movement whereby the travel of the lower line portion and the sheath thereon from the unit 35 is arranged to progressively form 70 the closed sheath about the line, the forward sheath end being fixed to the line as by means of the application of a clothes pin 29 over its forward end.

75 In its present embodiment, the unit 35 comprises a frame member 36 in the form of a plate

having transverse base extensions 37 whereby it may be mounted on the fixed support 38 which carries a pulley hook 33 and in parallel relation to the pulley 32 thereat. The extensions 37 may be provided with bayonet slot openings 39 for receiving the shanks of headed screws 40 engaged in the support 38; in this manner, the unit is arranged for removable mounting in its operative position.

Upper and lower stub shafts 42 and 43 extend 10 transversely from the plate 36 adjacent its outer end and in a common plane which is generally upright. The shaft 42 is rotatably fixed to the extremity of an arm 44 which is pivoted to the plate 36 and is urged downwardly through the 15 action of a leaf spring 45 which is coactive between it and a lug 46 extending from the upper plate edge. The shaft 43 is non-rotatably fixed in the plate 36, and the shafts 42 and 43 respectively carry rollers 47 and 48 for free rotation 20 thereabout and for mutually engaging a flattened portion of the sheath between them in the manner illustrated.

25 Preferably, the plate 36 is so disposed that the centers of the rollers 47 and 48 lie in the plane 25 of the adjacent line pulley 32 and so of the clothesline portion thereof whereby the sheath strip portion between the runner 15 and the rollers may be symmetrically opposite the underlying line portion. The roller treads are so formed 30 that they are arranged to bear solely on the interior portion of the tape and do not engage the fastening members at the tape edges. The roller 48 is shown as provided with radial end flanges for guiding the open and flattened sheath between them. A knob 49 is mounted at the free 35 end of the shaft 42 for use in lifting the roller 47 clear of the roller 48 for the insertion or removal of the sheath strip at the rollers.

40 A suitable guide member 51 is mounted on the plate 36 rearwardly of the rollers 47 and 48, and extends downwardly below and to one side of the lower clothesline strand on which the sheath is to be mounted. The member 51 provides a guideway trough which receives the tape to hold 45 it clear of the clothesline while guiding the sheath strip to or from the rollers, it being noted that the unmounted sheath portion below the member 51 may extend from a container 52 or a reel or even from the floor at the base of the 50 support 38.

An arm 53 extends forwardly from the bottom of the plate 36 to a point below the clothesline 31 at the runner 15, and is provided with means to engage and hold the tab 19 of the runner. 55 As shown in Figure 4, the arm 53 is provided with an upright opening 54 which receives the tab 19, and a slide bolt 55 on its upper side is engageable within the tab opening 20 when the tab is disposed in the opening 54. In this manner, the 60 runner is held against movement while the lower line strand is moved in or out to dismount or mount a sheath thereon.

65 With the present arrangement, the sheath 28 would be disposed for installation on the lower line strand by looping the front sheath end about the line, interengaging the bead 25 with the runner 15 and the member 22 in the described manner, effecting a slight rearward movement of the runner 15, applying a clothes pin 29 on the forward sheath portion, attaching the runner to the arm 53 by engaging its tab 19 with the bolt 55, and placing the flattened open sheath portion adjacent its forward end between the rollers 47 70 and 48 and in the guideway 51. It is noted that 75

all of the foregoing steps have been taken in the showing of Figure 1. An advancement of the lower line strand will now cause a secured closure of the sheath about the line, and the sheathed line may have the cloth articles mounted thereon as it is advanced.

A reverse movement of the sheathed line portion will progressively open the sheath, the clothes being removed as they approach the runner 15, or before, and the sheath being manually disengaged from the line and unit 35 when the runner reaches the forward sheath end. To avoid any slack in the sheath portion between the runner and the rollers 47 and 48, a crank arm 56 may be mounted on the outer end of the roller 48, the outer end of said arm carrying a knob 57 for manual operation to effect a pulling in of the sheath and line. When the sheath is being installed, the rollers would sufficiently resist the 20 operation to keep the sheath portion between the rollers and runner in taut condition.

It will be understood that the present sheath structure comprises a new and unitary article of manufacture, may be produced in any desired 25 lengths, and is applicable to elongated articles generally. And it will be further understood that the present sheath may be mounted on a clothesline without the provision and use of a runner holding means, as may be most desirable.

From the foregoing description taken in connection with the accompanying drawings, the advantages of the construction and method of operation of the present device will be readily understood by those skilled in the art to which 35 the invention appertains. While I have described the features and the application of the device in what I now consider to be a generally preferred embodiment thereof, I desire to have it understood that the showing is primarily illustrative, and that such changes may be made as fall within the scope of the following claims.

I claim:

1. In a clothesline sheath for mounting on a longitudinally movable clothesline, a strip of flexible material of uniform width for wrapped disposal about the line, rows of mutually complementary fastening members provided at and along the side edges of the strip and arranged for mutually interlocked engagement when the strip is formed into a closed tube with the members of the two rows disposed in alignment, a locking runner simultaneously engaging the fastening members of the two rows for engaging or disengaging said rows of fastening members as the strip and runner are relatively moved in the line of members, and means securing the runner against movement whereby a longitudinal movement of the line and sheath together is arranged to progressively close the sheath as the forward sheath end moves away from the runner and to progressively open the sheath as the forward sheath end moves toward the runner.

2. In a clothesline cover for mounting on a longitudinally movable clothesline, a strip of flexible material for shaping into a tubular sheath enclosing the line, rows of mutually complementary fastening member fixed at the side edges of the strip and arranged for mutually interlocked engagement when the strip is formed

into a laterally closed tube, a locking runner simultaneously engaging the fastening members of the two rows for engaging or disengaging said rows of fastening members, means securing the runner against movement whereby a longitudinal movement of the sheath is arranged to render the runner operative to open or close the sheath, rollers frictionally engaging an open sheath portion between them, and means to actuate a said roller to effect a longitudinal movement of the 10 closed sheath portion toward the runner.

3. In combination with a longitudinally movable clothesline, a strip of flexible material for wrapped disposal about the line to provide a sheath therefor, rows of mutually complementary 15 fastening members mounted at and along the side edges of the strip and arranged for mutually interlocked engagement when the strip is formed into a closed tube with the members of the two rows disposed in alignment, and an automatically 20 operative locking runner simultaneously engaging the fastening members of the two rows and arranged to be held against movement whereby a longitudinal movement of the line and sheath together is arranged to operate the locking 25 mechanism of the runner to progressively close the sheath as the forward sheath end moves away from the runner and to progressively open the sheath as the forward sheath end moves toward said runner.

4. In combination with a clothesline, a strip of flexible material for shaping into a tubular sheath enclosing the line, rows of mutually complementary fastening members mounted at the side edges of the strip and arranged for mutually 35 interlocked engagement when the strip is formed into a laterally closed sheath, a locking runner simultaneously engaging the fastening members of the two rows for engaging or disengaging said rows of fastening members, means securing the 40 runner against movement whereby a longitudinal movement of the sheath is arranged to render the runner operative to open or close the sheath, and means operative upon the sheath to effect a longitudinal movement thereof.

5. A structure in accordance with claim 4 wherein the last means progressively engages the open sheath portion at a fixed distance from the runner to effect a longitudinal movement of the closed sheath portion toward the runner to progressively open said portion at the runner.

6. In combination with a longitudinally movable clothesline, a strip of flexible material adapted for forming into a tubular sheath about the line, rows of mutually complementary fastening members mounted at the side edges of the strip and arranged for mutually interlocked engagement when the strip is formed into a sheath, a locking runner simultaneously engaging the fastening members of the two rows thereof, 55 means securing the strip to the clothesline at a closed point of the strip, and means securing the runner against movement whereby a longitudinal movement of the line to move the closed portion of the strip away from the runner is 60 arranged to progressively effect a closing of the sheath.

ADA P. WILLIAMS.
